Atty.

UNITED STATES PATENT OFFICE.

FREDERICK REYNOLD PETERSON, OF MELDEN, MASSACHUSETTS, ASSIGNOR TO
SAMUEL FINE, OF EAST BOSTON, MASSACHUSETTS.

CAPPED COLUMN.

Application filed October 23, 1919. Serial No. 332,723.

The present invention relates to supporting columns and more particularly to capped columns for supporting building structures and the like.

A common type of column of the above-described character comprises a casing the interior of which is filled with hardened concrete and which is surmounted by an enlarged cap. Upon the cap rests the supported structure, the weight of which is borne by the column. Two main types of cap are commonly employed, one of cast iron or steel, which is cast as a unit, and the other of which is a built-up cap constituted of separate steel or wrought iron parts and comprising a crown plate and supporting brackets therefor extending through the walls of the casing and anchored or embedded within the concrete contained therein. Neither of these types is entirely satisfactory, the cast-iron cap lacking the requisite stress-resisting properties and the supporting capacity of the steel or wrought iron brackets being necessarily limited by the degree of hardness of the concrete. The built-up cap, furthermore, is very expensive to build.

An object of the present invention is to provide an improved capped column of the above-described character.

Another object is to simplify the construction of caps and columns, increasing their strength, durability and efficiency and reducing their cost of manufacture.

To the attainment of these ends, a feature of the invention resides in integrally securing to the casing brackets having great stress-resisting characteristics, whereby the stress may be borne not by the concrete, as is the case with present-day built-up caps, but by the casing itself. The process of manufacture is thus greatly simplified and cheapened and the resulting cap is adapted to withstand greater stresses.

With the above and other objects in view, as will be apparent to persons skilled in the art, the invention consists of the improved capped column hereinafter described, illustrated in the accompanying drawings and defined in the appended claims.

In the accompanying drawings, Fig. 1 is a side elevation of a capped column con-

structed according to a preferred embodiment of the present invention; Fig. 2 is an underside plan view of the crown plate and its supporting brackets, with the casing shown in section along the line 2—2 of Fig. 1; Fig. 3 is a sectional view taken upon the line 3—3 of Fig. 2 looking in the direction of the arrows; Fig. 4 is a sectional view, taken upon the line 4—4 of Fig. 1, looking in the direction of the arrows; and Figs. 5, 6, 7 and 8 are views of details.

In the preferred form of the invention which is illustrated in the drawings, the capped column is shown as comprising an outer steel or wrought iron casing 2 surmounted by a cap 4 and adapted to receive within its walls a fire-proof filling 6, like concrete. The casing 2 is preferably cylindrical, but it may be of any desired shape, as rectangular, corrugated, fluted, etc.

The cap 4 comprises a plate 7 and a plurality of plate steel or wrought-iron reinforcing or supporting brackets therefor integrally secured to the casing 2. In the present instance, the brackets are integrally secured to the casing by welding. The brackets are shown simple in shape, unprovided with hooks or tenons of any kind whatsoever. For the sake of concreteness, the term "steel bracket" will be hereinafter employed to denote generically a bracket made either of steel or wrought iron. The plate 7 is shown as a crown plate, but it will be obvious that the invention is equally applicable to base plates. The term "crown plate" will accordingly be hereinafter employed for definiteness, but it will be understood to denote either a crown plate, properly so called, or a base plate. To facilitate the welding process, a plurality of slots 8 extend preferably longitudinally from one end of the casing. The walls of the slots taper, as illustrated more particularly at 10, Figs. 6 and 7. The space between the walls of the slots and the bracket and beyond is adapted to be filled with welding material 12 in a molten state and the parts welded together under a flame according to a well-known process, providing for a rigid union of the parts. The welding material 12 by

providing additional metal at the joint, affords added rigidity and strength.

The brackets may assume any of a number of different forms, two of which are illustrated at 14 and 16. The brackets 14 or the brackets 16 may be employed exclusively, or they may be employed in combination, as shown. The brackets 14 may extend through the slots 8, but preferably do not project into the interior of the casing 2, though they may be made of dimensions sufficiently great to permit of their so projecting, if desired. As shown, however, the inner sides of the brackets 14 are flush with the interior wall of the casing. Where diametrically opposed brackets are employed, the single plate bracket 16 may be employed, extending into and through two diametrically opposed slots 8. The ends of the plate bracket thereby aid in supporting each other. The intermediate portion 18 of the bracket 16 may be employed to secure the bracket to the crown plate 7. Any suitable securing means may be employed, such as angle irons 20 riveted to the bracket and to the crown plate. The brackets 14 may also be secured to the crown plate by angle irons and rivets, particularly if portions of the brackets project into the interior of the casing. As the provision of angle irons outside of the casing 2 would mar the appearance of the column, the brackets 14 may preferably be secured to the crown plate in the manner illustrated. For this purpose, a projection 22 is formed upon the bracket 14 adapted to enter an opening 24 in the crown plate, the walls of the opening tapering toward the bracket, as shown. The projection 22 is of greater dimension than the thickness of the crown plate, so as to provide for swaging the projection into the opening 24, as shown at 26, the parts becoming thus effectively secured together. Though a single projection 22 is shown as provided upon each bracket 14, it will be understood that as many projections may be employed as are deemed necessary. If preferred, the bracket 16 may be secured to the crown plate in the same manner.

The crown plate may be secured to the brackets either before or after the brackets are welded to the casing. If angle irons like those indicated by the numeral 20 are employed, the crown plate is preferably secured to the brackets before the brackets are secured to the casing. As the interior of the casing is not then usually accessible to the welding flame, the slots 8 should then be shaped as shown at Fig. 7. When both the exterior and the interior may be exposed to the flame, the walls of the slot 8 may be shaped as shown in Fig. 6. In the former event, the welding material and the welding flame will be applied to the exterior of the casing only; in the latter event, they will be applied to both the exterior and the interior. If desired, the crown plate

may also be welded to the casing, and to facilitate such welding, the end of the casing may be bevelled as shown at 28, Fig. 5, so that the molten welding material may be applied under the welding flame in the space between the casing and the crown plate.

In order that floor beams, girders, rafters and the like may be supported by the column at different elevations, additional crown plates 30 may be provided upon the sides of the column at any desired positions spaced from the crown plate 7. The crown plates 30 may be supported by re-enforcing brackets 32 secured to the casing as above described, and may extend within transverso slots 34 of the casing to the walls of which the crown plates 30 may be welded if desired as indicated in Fig. 8.

After the metal parts of the column have been completed, the column may be turned end for end and a filling of plastic material, like concrete in plastic form, poured thereinto and allowed to harden, rendering the column strong, durable and fireproof.

It will be noted that the cap is secured directly to, and is supported entirely by, the casing, and does not require to be anchored to or imbedded in the concrete, as is customary with built-up columns and caps of the present day. The parts are rigidly secured at the joints so that no additional securing means of any sort, such as reinforcing rods are required other than those which secure the crown plate to the brackets.

The improved cap of the present invention is much stronger, more durable and more efficient than any which have been heretofore proposed, is fireproof, resisting the effects of fire without warping or cracking, and may be manufactured at small cost.

It will be understood that the invention is not limited to the exact embodiment thereof which is herein illustrated and described, but that changes may be made therein by the skilled artisan without departing from its spirit and scope as defined by the appended claims.

I claim:

1. A built-up column comprising a concrete-filled casing having a longitudinally disposed slot, and a built-up steel cap comprising a steel crown plate and a steel plate bracket supporting the crown plate, the plate bracket being disposed in the slot with the plane of the plate bracket disposed longitudinally of the casing, and the plate bracket being rigidly secured directly to the casing independently of the concrete by welding.

2. A built-up column having a slot and a bracket within the slot welded to the walls thereof.

3. A built-up column having a slot, a bracket within the slot welded to the walls

thereof, and a crown plate supported by the bracket.

4. A built-up concrete-filled column comprising a casing having a slot extending longitudinally from one end thereof, a plate bracket extending into the slot welded to the walls thereof, and a crown plate secured to the bracket.

5. A built-up column comprising a casing having a longitudinally extending slot the walls of which taper, a bracket extending into the slot welded to the walls thereof with welding material which fills the space between the walls of the slot and the bracket and beyond, and a crown plate supported by the bracket.

6. A built-up column comprising a casing having a slot, a bracket within the slot welded to the walls thereof and a crown plate supported by the bracket and welded to the casing.

7. A built-up column having a slot extending longitudinally from an end thereof, a bracket within the slot welded to the walls thereof having a projection, and a crown plate supported upon said end and having an opening to receive said projection, the walls of the opening tapering towards the bracket and the projection being swaged into the opening.

8. A built-up column having a plurality of slots extending from an end thereof, a bracket in each of said slots welded to the walls thereof, and a crown plate supported upon said end and said brackets.

9. A built-up, concrete-filled column comprising a casing having a plurality of slots extending longitudinally from an end thereof, a bracket within each of the slots welded to the walls thereof, and a crown plate resting upon said end secured to the brackets.

10. A built-up column comprising a casing having a longitudinally extending slot, and a plate bracket within the slot welded to the walls thereof, the inner side of said bracket being flush with the interior wall of the casing.

11. A built-up column having two diametrically opposed slots, a bracket extending into the column through said slots and welded to the wall of said slots, and a crown plate supported by said bracket.

12. A built-up column having three slots extending longitudinally from an end thereof, a bracket extending through two of said slots and welded to the walls thereof, a bracket within the third slot and welded to its walls, and a crown plate supported by said brackets.

13. A built-up column having a longitudinally extending slot spaced from an end thereof, a plate bracket within the slot welded to the walls thereof having an upwardly extending projection, and a crown plate supported by the bracket having an

opening within which the projection is swaged to secure the crown plate to the bracket.

14. A built-up column having a slot extending longitudinally from an end thereof, a plate bracket within the slot welded to the walls thereof having a projection, the inner side of said bracket being flush with the interior of the column, and a plate supported upon said end having an opening to receive said projection, said projection being swaged within said opening to secure said plate to said bracket.

15. A built-up column having two diametrically opposed slots, a simple, plate bracket extending into the column through said slots and secured to the walls of said slots by welding only, and a crown plate secured to said bracket.

16. The method of making a built-up column which comprises slotting a casing, inserting a plate into the slot, and integrally uniting the plate to the walls of the slot by welding.

17. The method of making a built-up column which comprises longitudinally slotting a casing so as to make the walls of the slot tapering, inserting a plate bracket into the slot, integrally uniting the bracket to the walls of the slot by welding with welding material which fills the space between the walls of the slot and the bracket and beyond, providing a projection upon the bracket, providing a corresponding opening in a crown plate, mounting the crown plate upon the bracket with the projection in the opening, swaging the projection into the opening, and welding the crown plate to the casing.

18. The method of making a built-up column which comprises slotting a casing, inserting a plate bracket into the slot, welding the plate to the walls of the slot, and securing a crown plate to the bracket.

19. The method of making a built-up column which comprises longitudinally slotting a casing at an end thereof, inserting a plate bracket into the slot, welding the bracket to the walls of the slot, mounting a crown plate upon said end so as to be supported by the bracket, and welding the crown plate to the casing.

20. The method of making a built-up column which comprises longitudinally slotting a casing at an end thereof, forming a projection upon a plate bracket, inserting the bracket into the slot, welding the bracket to the walls of the slot, forming a tapering opening in a crown plate, mounting the crown plate upon said end of the casing so as to be supported by the bracket with the projection in the opening and the smaller end of the opening adjacent to the bracket.

and swaging the projection into the opening.

21. The method of making a built-up column which comprises longitudinally slotting a casing at a plurality of points at an end of the casing, inserting a plate bracket in each of the slots, welding the brackets to the walls of the corresponding slots, and securing a crown plate to the brackets.
22. The method of making a built-up column which comprises longitudinally slotting a casing at two diametrically opposite points at an end of the casing, inserting a plate bracket into the column through the slots, welding the bracket to the walls of the slots, and securing a crown plate to the bracket.
23. The method of making a built-up column which comprises longitudinally slotting an end of a casing at three points, inserting a plate bracket into the column through two of the slots, and another plate bracket in the third slot, welding the brackets to the walls of the corresponding slots, and securing a crown plate to the brackets.
24. A building column comprising a casing provided with a slot, a bracket in the slot, the slot edges and bracket being welded together, and a top plate resting on the bracket and secured to the column.
25. A building column comprising a casing, a bracket thereon, a lug on said bracket and an apertured top plate the aperture of which engages the bracket lug.
26. A building column comprising a slotted casing, the slots being opposed, a bracket in said slots, lugs on the bracket and a top plate provided with apertures engaging the bracket lugs, the bracket and slot edges being welded together.
27. A building column comprising a casing provided with slots, a bracket in each of said slots extending within and beyond the casing, integral lugs on the top of said brackets and an apertured top plate, the apertures of which engage the lugs, the slot edges and brackets being welded together.
28. A building column comprising a casing provided with a slot, a bracket in said slot and partly within and partly without said casing, the edges of the slot being welded to the side faces of the bracket, a top plate resting on the casing and bracket and secured thereto and a plastic filling within said casing.
29. A building column comprising a casing provided with opposed slots, a bracket in said slots extending outside of and through said casing, the edges of the slots and side faces of the brackets being welded together, and a top plate resting on the brackets and secured to the column.
30. A building column comprising a casing provided with a slot, a bracket in said slot, a top plate resting on the bracket and casing end, the top plate and casing end being welded together whereby spreading of the slot is prevented.

In testimony whereof, I have hereunto subscribed my name this 18th day of October, 1919.

FREDERICK REYNOLD PETERSON.
